UNITED STATES PATENT OFFICE

142,102

DESIGN FOR A LOCOMOTIVE BODY

John Markestein, North Riverside, Ill., assignor to
General Motors Corporation, Detroit, Mich., a
corporation of Delaware

Application June 15, 1945, Serial No. 120,115

Term of patent 14 years

(Cl. D66—1)

To all whom it may concern:

Be it known that I, John Markestein, a citizen
of the United States, being a resident of North
Riverside, county of Cook, State of Illinois, have
invented a new, original, and ornamental Design
for a Locomotive Body, of which the following is
a specification, reference being made to the ac-
companying drawing forming a part thereof.

In the drawing:

Fig. 1 is a plan view of a locomotive body show-
ing my design.

Fig. 2 is a side elevational view of the body.

Fig. 3 is a front elevational view thereof.

Fig. 4 is a perspective view, as seen from a point
in front of and at the side of the body.

The appearance of the side of the body oppo-
site to that shown is substantially the same as
that shown, and the rear end portion of the loco-
motive body design is conventional.

I claim:

The ornamental design for a locomotive body,
substantially as shown and described.

JOHN MARKESTEIN.
